UNITED STATES PATENT OFFICE.

ALBERT RODGERS WARNER, OF PHILADELPHIA, PENNSYLVANIA.

HYDROCARBON-VAPOR-BURNING LAMP.

SPECIFICATION forming part of Letters Patent No. 681,282, dated August 27, 1901.

Application filed June 26, 1900. Serial No. 21,610. (No model.)

To all whom it may concern:

Be it known that I, ALBERT RODGERS WARNER, a citizen of the United States, residing at No. 2020 Oxford street, in the city of Philadelphia, in the county of Philadelphia and State of Pennsylvania, have invented certain new and useful Improvements in Hydrocarbon-Vapor-Burning Lamps, of which the following is a specification.

10 My invention has relation to improvements in a hydrocarbon-vapor-burning lamp of the form which has become known as a "suspension-lamp," employing two or more mantles adapted to become incandescent and now 15 commonly known as "Welsbach" mantles, and a lamp in which hydrocarbon oil is thoroughly vaporized and afterward mixed with air prior to its consumption in the burners of the lamp; and in such connection it relates 20 more particularly to the construction of the lamp and arrangement of the parts of the same for the said purposes.

25 My invention, stated in general terms, consists of a hydrocarbon-vapor-burning lamp when constructed and arranged in substantially the manner hereinafter described and claimed.

30 The nature and scope of my present invention will be more fully understood from the following description, taken in connection with the accompanying drawings, forming part hereof, in which—

Figure 1 is a vertical longitudinal sectional view of a lamp embodying main features of 35 my invention. Fig. 2 is a vertical sectional view of the upper portion of the lamp on the line $\alpha\alpha$ of Fig. 3. Fig. 3 is a cross-sectional view on the line 33 of Fig. 1. Fig. 4 is a view, partly in section and partly in elevation, of 40 the vaporizing-tubes; and Fig. 5 is a vertical sectional view of a portion of the burner-body and in broken section of a portion of the mantle connected therewith.

45 Referring to the drawings, A represents an exterior casing or hood surrounding a portion of the working parts of the lamp. Beneath said casing is suitably secured a globe a , within which is confined two or more incandescent mantles b and b' , suspended from the 50 bodies of the burners c and c' . The burner-bodies c and c' are connected directly with a vapor-expanding chamber d , arranged trans-

versely of the lamp and communicating with a vaporizing-coil d^4 and tube d' , into which the oil is fed under pressure by means of a 55 pipe d^2 from a suitable source of oil-supply (not shown) and in which the oil is vaporized. This oil-supply, in its connection with the vaporizing-coil d^4 and tube d' , is provided with a check-valve or stop-cock d^3 , which controls the supply of oil entering the vaporizing-coil d^4 and tube d' . Above the vaporizing-coil d^4 and tube d' is located a jet-tube e , connected with a source of independent gas-supply and controlled by an electric gas-igniting 60 device E , of any well-known type—for instance, a magnetic device, as illustrated. This device is connected by lines 1 and 2 with a battery m and operated by push-buttons m' and m^2 , as illustrated in Fig. 1, one push-button serving to turn on the gas and to ignite the same, whereas the other stops the flow of gas.

The sparking device consists of two wires g and g' of the electric igniter E , and they are 75 located adjacent to the end of the jet-tube e , as clearly illustrated in Figs. 1 and 2, whereby when the current is made by the operation of one or the other of the push-buttons m' or m^2 the gas passing through the jet-tube e is ignited. The jet by striking upon the tube d' is divided into two small flames e^2 and e^3 , one branch e^2 being directed upon the coil d^4 and the other branch e^3 of the flame being deflected in the direction of and against 80 the burner-bodies c and c' for effecting the ignition of the gases issuing from the burners. The division of the flame issuing from the jet-tube is induced by the deflecting of the flame to the side of the vaporizing-tube 85 d' in order that one portion of said flame under pressure may be directed through the coil of the vaporizing-tube d' for heating the same to a high degree, and thereby hastening the initial vaporization of the oil in its passage 90 through said tube and anterior to the expansion of the vaporized oil in the chamber or tube d , as illustrated in Figs. 2 and 4. After initial vaporization the flow of gas through the jet-tube e is cut off by means of one of the 100 push-buttons m' or m^2 , and thereafter the heat of the burners c and c' continues the vaporization of the oil flowing through the vaporizing-coil d^4 , tube d' , and chamber d .

The expansion of vapor in the chamber *d* is sufficient to induce sufficient pressure to project the vaporized oil downward through the burners *c* and *c'* with sufficient force as that 5 when ignited the flames will properly incandesce the entire body of the respective mantles *b* and *b'*. The expanding-chamber *d*, being highly heated, serves further to vaporize all particles of oil escaping through the coil 10 *d*⁴ and tube *d'* before the vapor reaches the burner. The entrance of air into the globe for supporting combustion of issuing ignited gases at the burners in the presence of the mantles is always under less pressure than 15 the downward pressure of the flame from the burners, thus insuring a uniform and high degree of illumination from said mantles.

i and *i'* are vertical air-tubes extending through the exhaust chamber or receptacle 20 *D* of the lamp. These tubes conduct air from the exterior of the chamber *D* to the burners. From the base of the said chamber or receptacle *D* is suspended the globe *a*, suitably clamped thereto. The receptacle *D* and globe 25 *a* together form a substantially air-tight inclosure for the working parts of the lamp, and the vertical tubes are secured at their upper ends in stuffing-boxes *h*² and *h*³ and traverse the receptacle *D* and open out into the external air, as clearly illustrated in Fig. 2. The provision of stuffing-boxes at the upper ends 30 of the tubes *i* and *i'* permits said tubes *i* and *i'* to expand or contract under variations of temperature without impairing the air-tight character of the inclosure for the working parts. 35

The vaporizing-tube *d'* at the point of junction of the oil-supply therewith is provided with a stuffing-box *j*, similar to those already described, to compensate for expansion or contraction of this tube when either in or out of use.

Within each of the burner-bodies *c* and *c'* is provided a vertical tube *k*, made tapering at its lower extremity, and within which body 45 and below said tube *k* are provided a series of superposed truncated-cone-shaped open-ended hoods *k'*, acting on the injector principle, to permit of more complete commingling of the air fed by the tube *i* or *i'* to the gas entering the burner-body *c* or *c'*, and thus to effect more uniform or complete admixture of the air with the gas prior to consuming of the gas at the burners.

From the upper part of the exhaust-chamber *D* is provided a tube or off-take *n*, surrounded by asbestos or other heat-non-conducting material *o*, as illustrated in Figs. 1 and 2, whereby the heat generated by the lamp, as well as the gases of combustion, may 55 be conveyed from the lamp-body to a point outside the apartment to which the lamp is hung without materially affecting the temperature of the apartment and at the same time the lamp with its working parts and the 60 globe within which is confined the burners maintained air-tight.

The noises incident to the pressure under

which the gases are delivered to the burner by this type of vapor-burning lamp are not only lessened, but also deadened. The smell of un- 70 vaporized and unconsumed oil and the drip of free oil from the burners is avoided by passing the oil after vaporization in the coil *d*⁴ into the expanding-chamber *d* prior to its delivery to the burners and prior to its mix- 75 ture with air. Moreover, the lamp is more efficient due to the manner of ignition of the gas through the divided jets by the sparking device of the electric igniter. Again, by arranging the parts of the lamp as described 80 and illustrated the lowering of the lamp for lighting is avoided, because the starting of vaporization of the oil as well as the lighting of the burners of the lamps are under control through the said electric igniting device *E*. 85

Having thus described the nature and objects of my invention, what I claim as new, and desire to secure by Letters Patent, is—

1. In a hydrocarbon-vapor-burning lamp, a substantially air-tight receptacle, a series 90 of burners comprising burner-bodies, a vaporizing-coil and an expanding-chamber contained within the air-tight receptacle, said coil and chamber being located above the burners and arranged to be heated thereby, 95 said coil communicating at one end with the oil-supply pipe and at its other end discharging into said expanding-chamber, said expanding-chamber being arranged to discharge 100 into the burner-bodies, and an air-inlet tube leading from the exterior of the receptacle to each burner-body and entering said burner-body adjacent to the communication of the expanding-chamber with said burner-body, substantially as and for the purposes de- 105 scribed.

2. In a hydrocarbon-vapor-burning lamp, a substantially air-tight chamber, comprising an upper receptacle and a lower globe, an exhaust-tube provided with a heat non-conducting covering leading from the upper receptacle and arranged to receive and conduct the exhaust-gases from the lamp, a series of burner-bodies contained within the globe and below the receptacle and exhaust, a burner 110 supported by each burner-body, and an air-inlet pipe for each burner-body traversing the interior of the upper receptacle and in open communication at one end with the exterior of the receptacle, said air-inlet pipe 115 arranged to enter the burner-body, substantially as and for the purposes described.

3. In a hydrocarbon-vapor-burning lamp, a chamber supporting a globe and provided with an offtake, a vaporizing-tube, a vapor-expanding chamber having the burner-body connected therewith and located within said globe, a gas-jet tube located adjacent to said vaporizing-tube, and the latter dividing the flame issuing from said gas-jet tube, and air-inlet pipes connected with said burner-body and mounted in stuffing-boxes in the top of said chamber, substantially as and for the purposes described. 125 130

4. In a hydrocarbon-vapor-burning lamp, an exhaust-chamber provided with an off-take and supporting a globe, a vaporizing-tube and a vapor-expanding chamber located in said exhaust-chamber, said vapor-expanding chamber supporting burner-bodies, air-supply tubes connected to the burner-bodies and said bodies provided with vertical pipes made tapering at their lower extremities and within which bodies and below said pipes are located a series of superposed open-ended

hoods for permitting of more complete commingling of air with the vapors issuing from said vapor-expanding chamber, substantially as and for the purposes described.

15

In testimony whereof I have hereunto set my signature in the presence of two subscribing witnesses.
